UNITED STATES PATENT OFFICE

2,236,362

REFRIGERATOR CAR

Charles D. Bonsall, Pittsburgh, Pa., assignor, by
mesne assignments, to Standard Railway Re-
frigerator Company, a corporation of Delaware

Original application November 16, 1936, Serial No.
111,058. Divided and this application Novem-
ber 2, 1938, Serial No. 238,442

4 Claims. (Cl. 62—17)

The device or system relates to insulated re-
frigerator cars used to transport perishable com-
modities, such as vegetables, fruits, berries, meats,
eggs, frozen fish, etc., and to maintain such com-
modities while in transit within a predetermined
range of temperatures, thus necessitating the use
of a cooling means in the summer and a heating
means in the winter. It has been found that
perishable commodities which have not been
allowed to get too cold (freeze) or too hot (bake)
have a high market value because they have a
longer storage life.

The invention relates more specifically to the
type of refrigerator car disclosed in the patent
of which this is a division; that is, Bonsall No.
2,136,999, filed November 16, 1936, wherein re-
frigerant containers are positioned adjacent the
roof of the car and filled through hatches in
such roof and associated with other elements in
the car or forming part thereof so that air cooled
by the refrigerant in the container is directed
through a duct associated with a vertical wall of
the refrigerator to a space under the lading
from which it rises, and being warmed by the
lading, enters the zone of influence of the re-
frigerant, and again being cooled thereby, re-
peats the cycle.

The object of the invention is to provide such
a refrigerant container with outer solid walls
and solid bottom to retain the melted ice, brine
or other refrigerant, and to provide a forami-
nous basket within the solid container to keep
the solid refrigerant away from the bottom (and
also preferably the side walls thereof) of the
container so that air may circulate around the
refrigerant and cool the circulating air in the
flue provided below the refrigerant. In the case
of wet ice, the object is to keep the wet ice away
from the bottom of the container so that the
melted ice or ice water may freely drain to
an outlet provided for that purpose. In such a
case the ice water will cool the circulating air
in the flue provided below the container.

In the drawings:

Fig. 1 shows a typical cross section of a refrig-
erator car incorporating my improved refrig-
erant container.

Fig. 2 is a longitudinal section of the car shown
in Fig. 1.

Fig. 3 is a diagram showing a typical relation
of the refrigerant container to the other parts
of the car.

My invention is adaptable to a refrigerator car
having spaced apart insulated car walls 2; insu-
lated roof 3; insulated floor 4; foraminous floor

or floor rack 5 above the insulated floor 3 and
an air space 6 between said floors.

As shown diagrammatically in Fig. 3 the re-
frigerant in the container 8 cools the air in flue
10 so that it flows downwardly through the duct 5
12 into the space 6 below the foraminous floor
5, and being warmed by the lading, rises and
enters the passageway 14, thence into the flue
10, and being again cooled by the refrigerant,
repeats the cycle.

A foraminous basket 20 is set into an outer
container 22 having solid walls 24 and solid
bottom 26 with foraminous walls 28 and bottom
30 of the basket 20 spaced apart from the solid
walls and bottom respectively of the container
15 to provide air flues 32 and 34 therebetween so
that wet ice may be used as a refrigerant by put-
ting such ice in the foraminous basket 20 so that
air will circulate between the foraminous walls
thereof and the solid walls of the container and 20
also between the solid bottom of the container
and the foraminous bottom of the basket. When
brine (or other liquid) is used as a refrigerant
it may be confined by the solid walls 24 and bot-
tom 26 of the container and cools the circulating
air in the flue 34 below the container. A drain
25 having a water seal may be provided for the
container, which drain is provided with a closing
valve, if desired. When brine is being used as a
refrigerant, the foraminous basket 20 retards 30
the movement of the liquid brine, due to the
movement of the car.

The bottom of the foraminous basket 30 con-
stitutes a secondary foraminous floor in spaced
relation to the bottom 26 of the outer container 35
to keep a solid refrigerant out of contact with
the solid bottom 26 of the container. When
wet ice is used as a refrigerant the melted ice
or ice water is not retarded by the solid refrig-
erant in its movement toward the drain. The 40
bottom 26 of the refrigerant container prefer-
ably slopes downwardly toward the drain.

The foraminous basket 20 may be made of
wire netting, as shown, of a perforated metallic
plate or similar structures.

This is a division of my application Serial No.
111,058, filed November 16, 1936.

The accompanying drawings illustrate the pre-
ferred form of the invention, though it is to be
understood that the invention is not limited to
the exact details of construction shown and de-
scribed, as it is obvious that various modifica-
tions thereof, within the scope of the claims, will
occur to persons skilled in the art.

I claim:

- 5 1. In a refrigerator car, a refrigerant container disposed so that air circulating within the car is cooled thereby, said container comprising an outer member having solid bottom and solid walls and a foraminous inner member having some of the walls thereof spaced from said outer member to provide a flue for air movement and an air inlet opening to said flue whereby some of said air flows through said flue and is cooled by contact with a refrigerant in said inner member.
- 10 2. In a refrigerator car, a refrigerant container disposed so that air circulating within the car is cooled thereby, said container comprising an outer member having solid bottom and solid walls, a foraminous inner member having some of the walls thereof spaced from said outer member to provide a flue for air movement, an air inlet opening to said flue whereby some of said air flows through said flue and is cooled by contact with a refrigerant in said inner member, and means to drain a liquid from said outer member.
- 15 3. In a refrigerator car, a refrigerant container disposed so that air circulating within the car is cooled thereby, said container comprising an

outer member having solid bottom and solid walls, a foraminous inner member having some of the walls thereof spaced from said outer member to provide a flue for air movement, an air inlet opening to said flue and means to drain a liquid 5 from said outer member, the bottom of said outer member sloping downwardly toward said means.

4. In a refrigerator car having a refrigerant container below the roof and adjacent one of the walls, a duct associated with said wall, and an 10 enclosing structure for said container having a cold air discharge opening leading to said duct and an air inlet opening at a higher elevation than said discharge opening, said structure being spaced from said container to provide a flue 15 therebetween, said container comprising an outer member having solid bottom and walls and an inner foraminous member spaced from said outer member to provide a flue, an air inlet opening to the last mentioned flue so that part of the 20 air flowing through the first mentioned inlet opening passes through said first mentioned flue and the other part through said second mentioned flue.

CHARLES D. BONSALL. 25
